Specification for Design.

Patented Mar. 29, 1921.

Application filed October 1, 1920. Serial No. 414,116. Term of patent 3½ years.

To all whom it may concern:

Be it known that I, ABRAHAM M. TURKELTAUB, a citizen of the United States, residing at No. 740 West End avenue, city of New York, county of New York, and State of New York, have invented a new, original, and ornamental Design for Buttons, of which the following is a specification, reference being had to the accompanying drawing, forming part thereof.

Figure 1 is a front face view of a button, showing my new design.

Fig. 2 is a side elevation of a button, showing my new design.

I claim:

The ornamental design for a button as shown.

ABRAHAM M. TURKELTAUB.
